UNITED STATES PATENT OFFICE.

HENRY J. DAVIES, OF BROOKLYN, NEW YORK.

DESIGN FOR A CLOCK-CASE.

SPECIFICATION forming part of Design No. 13,142, dated August 8, 1882.

Application filed June 24, 1882. Term of patent 7 years.

To all whom it may concern:

Be it known that I, HENRY J. DAVIES, of Brooklyn, in the county of Kings and State of New York, have originated and produced a certain new Design for Clock-Cases, of which

5 the following is a specification.

My design for a clock-case consists in the representation of a hat having the dial of the clock in the tip of the crown.

10 The accompanying drawing represents a perspective view of a clock-case embodying my design.

A designates the brim of the hat, which is rolled up at one side, A', and which, as shown, 15 has its outer side ribbed or corrugated slightly at a, in order to simulate the appearance of braided and sewed straw.

B designates the side crown, and C the dial, which is located at the tip of the crown of the 20 hat.

D designates the clock-hands.

In order to give the clock-case a more attractive appearance, I encircle the side crown, B, with a ribbon or band, E, tied in a bow, E'.

A clock having a case of this design when 25 hung upon the wall, will present the appearance of a hat hung upon the wall and having a clock in its crown.

What I claim, and desire to secure by Letters Patent, is—

The design for a clock-case, consisting in the representation of a hat having the clock-dial in the tip of its crown, as herein shown and described.

HENRY J. DAVIES.
